(57) **CLAIM**

The ornamental design for a open-top tent, as shown and described.

DESCRIPTION

FIG. 1 is a front perspective view of the open-top tent of the present invention;

FIG. 2 is a rear perspective view thereof;

FIG. 3 is a top plan view thereof;

FIG. 4 is a right-side view thereof;

FIG. 5 is a left-side view thereof;

FIG. 6 is a front side view thereof; and,

FIG. 7 is a rear side view thereof.

The dot-dashed lines around the outer edges in the magnified views are symbolic boundary lines and are not a part of the claimed design. The broken lines showing tent poles throughout the views are for clarity and to provide context, but the broken lines form no part of the claimed design.
